UNITED STATES PATENT OFFICE.

GEORGE B. PUTNAM, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,018,371.

Specification of Letters Patent. Patented Feb. 20, 1912.

Application filed May 14, 1907, Serial No. 373,573. Renewed June 3, 1910. Serial No. 564,857.

To all whom it may concern:

Be it known that I, GEORGE B. PUTNAM, residing at Detroit, in the county of Wayne and State of Michigan, have invented certain new and useful Improvements in Adding-Machines, of which the following is a specification.

Letters Patent No. 825,205, issued July 3, 1906, to Burroughs Adding Machine Company upon the invention of Claiborne W. Gooch, disclose a machine equipped with devices for effecting what is known in the art as a "split". In the machine of said patent a special key is provided which when depressed operates to uncouple adjacent latches of the set or gang usually employed in the well-known Burroughs adding and listing machine for controlling the action of impression hammers. By so uncoupling adjacent latches the automatic tripping of latches from left to right for cipher printing purposes is caused to terminate at a predetermined point. Hence the machine is said to be split into two sections or divisions so that two separate and distinct columns of numerals can be simultaneously printed in one series of operations of the machine. This is found useful *e. g.* where designating numbers or dates are desired in tabulation opposite the several amounts the sum total of which is being accumulated. Gooch's invention made provision for fitting up the machine to be thus split at any point from side to side of the transverse series of denominational recording and registering devices. His invention also provided for splitting the machine at more than one point at the same time so that any extent of subdivision desired might be had. The latter provision of the Gooch invention contemplated the employment of a plurality of special couplings between the hammer-controlling latches and manipulative means for disabling the same in order to effect splits at the desired points. The Gooch invention also extended to the provision of means whereby the printing of a total would be prevented in that section or division of the machine which under a split condition of the machine might be employed merely for the recording of designating numbers or dates.

It will be understood that a machine having the Gooch "split" contains the customary accumulator made up of independ-

ently movable counting members one for each decimal or denominational place up to the full capacity of the entire key-board and usually one or more beyond. The operation of this accumulator, including transfer or "carrying one" to higher denominational members as lower denominational members reach the limit of their counting capacity, is not affected by the so-called "splitting" of the machine. The character of tabulating work for which the "split" makes provision is seldom if ever such as to run the accumulation in the right-hand division of the split machine so high as to encroach upon that section or division of the accumulator which pertains to the left-hand section or division of the split machine. When this left-hand section or division is employed merely for listing designating numbers or dates of course the accumulation is of no moment. However, it is not generally considered desirable to provide means for disabling the accumulator throughout that part pertaining to this left-hand section or division of the machine as this would entail needless complication. However, it is desirable in order to avoid confusion in recording that the accumulated total of recorded designating numbers or dates be not printed at the foot of the column of such numbers when a total is being taken of the amounts recorded opposite these designating numbers. The Gooch invention provided for preventing operation of the hammers of the left-hand section or division of the split machine in a totalizing operation by blocking such hammers thereby preventing any movement of them when unlatched.

One object of the present invention is to provide for eliminating the imprint of the total when the machine is split for the listing of numbers not requiring accumulation, by preventing percussive action of hammers rather than actually blocking the movements of such hammers as Gooch did.

Another object of the invention is to provide improved manipulating means whereby to determine whether or not the machine shall be split and if split whether or not totals shall be printed at the foot of all columns. Thus the character of manipulative means of the present invention provides for location of a finger-piece upon the key-board of the machine in such position as to indicate the line of split. Provision is also made

for denoting by words or abbreviations upon this finger-piece the condition in which the machine stands.

With these and incidental objects in view the invention consists in certain novel features of construction and combinations of parts the essential elements whereof are recited in the appended claims and a preferred form of embodiment of which is described in detail hereinafter and fully illustrated in the accompanying drawings forming part of this specification.

Of said drawings Figure 1 represents in left side elevation an adding and listing machine of the Burroughs type having the improvements of the present invention embodied therein, the inclosing casing of the machine being shown in section as well as certain cross-rods and shafts and the paper carriage attachment at the rear; Fig. 2 shows part of the machine in left-side elevation with a limited portion in section, the normal condition being here represented *i. e.* the condition when there is no split; Fig. 3 represents in plan view a fragment of the keyboard under similar conditions; Fig. 4 represents a detail cross-section on the line 4—4 of Fig. 2; Fig. 5 represents a vertical section from front to rear of a limited portion of the machine viewed from the right under the normal condition above mentioned; Fig. 6 is a horizontal section taken substantially on the line 6—6 of Fig. 5; Fig. 7 is a view somewhat similar to Fig. 2 but with the machine split and arranged not to print a total at the left of the split, dotted lines illustrating the effect of the adjustment in this regard; and Fig. 8 is a view similar to the left-hand portion of Fig. 7 but under an adjustment which while providing for the split does not eliminate the total imprint at the left of the split.

The invention is here shown by preference embodied in an adding and listing machine of the well-known Burroughs type, an example of which is to be found in said Gooch patent and for other details of which reference may be had to the William S. Burroughs Patents Nos. 504,963 and 505,078, issued September 12, 1893. In view of the disclosures in these and other prior patents owned by Burroughs Adding Machine Company and also the presence on the market of the Burroughs machine in large numbers it will not be necessary to extend this specification to a detailed description covering all of the characteristics of said machine. It will suffice to particularize only as to the parts thereof with which the present invention is more closely related. While the embodiment of the invention illustrated in the accompanying drawings is especially adapted to this well-known Burroughs machine the invention is not to be understood

as necessarily so limited in its application as it is capable of adaptation to other types of adding and listing machines.

The reference numeral 291 designates the usual amount keys arranged in parallel rows extending from front to rear at the top of the machine and adapted to severally release and set stops for the usual segmental racks 610 which coöperate with pinions 916 of the accumulator 990, the latter being carried in a rocking frame 910. The reference numeral 293 designates the usual total key for timing the movements of said rocking frame when totals or sub-totals are printed, this key as usual surmounting the upstanding portion of one arm of a bell-crank lever 227L secured to a rock-shaft 204, (Figs. 2 and 7).

The reference numeral 611 designates the customary arms or levers, independently pivoted upon the rocking cross-shaft 600 and carrying at their forward ends the segmental racks and at their rear ends the sets of type-plates 618 respectively. The reference numeral 613 designates the usual restoring frame carried by said shaft 600 and vibrating in each operation of the machine to first retreat from said arms or levers 611 and then restore the same to normal position. The type-plates are as usual driven against a roller platen 1799 journaled in a carriage 1700 which is mounted to shift laterally upon suitable tracks or ways of a bracket 1701 secured to the rear side of the machine casing. Hammers 715 independently pivoted upon a rod 701 strike the type-plates to do the printing, said hammers being actuated by drivers 716 independently pivoted upon a cross-rod 702 and impelled by springs 780, these drivers being normally held against the stress of said springs by a bail 712 also pivoted upon said cross-rod 702 (Fig. 5). This bail is connected through the medium of a link 729 with a plate 823 carried by a rock-shaft 800 which is oscillated in each operation of the machine. Latches 717 independently pivoted upon a cross-rod 700 engage the drivers respectively and pawls 718 operate in the usual manner to severally trip said latches, these pawls being independently pivoted upon the cross-rod of an oscillating bail 704 and yieldingly held in engagement with the latches by the springs 780. The tails of the pawls coöperate as usual with inclined shoulders on the several levers 611 to effect automatic disablement of pawls when no type-setting movements of corresponding levers 611 take place.

It is customary in the Burroughs machine to form the latches 717 with overlapping tails so that there will ensue a tripping or displacement of all latches to the right of that one pertaining to the row of keys representing the highest denominational or

decimal place in the amount to be registered and recorded or the total or sub-total to be struck, notwithstanding there may be no type-setting movement of one or more of the levers 611 so located to the right. In the Gooch construction these overlapping tails are employed for transmitting movement from one latch to another in any one set of latches on either side of a split but at the line of a split the overlapping tail is omitted and a movable coupling device takes its place. A similar construction is employed in the present case.

By reference to Fig. 6 it will be observed that the latch 717 farthest to the left is provided with a tail *b* which overlaps the adjacent latch but the latter has no such tail there being interposed between this latch and the next one to the right a coupler bar 1315 carrying at its rear end oppositely projecting studs 717^b to occupy notches in the latches so that movement may be transmitted from the second to the third latch through the medium of this coupling bar which at its forward portion is bifurcated to embrace a guide and pivot shaft 1301. The third latch to the right is formed with a tail which overlaps the fourth latch but the latter has no tail and between it and the fifth latch is arranged another of the coupler bars 1315. All the latches to the right beyond the fourth except the last one to the right are shown with the overlapping tails. Thus it will be observed that provision is made for two splits so that three columns of numbers may be listed. The number of splits is not material nor their location which may be changed at will by re-assembling the coupler bars and latches. To this end the latches straddle a pivot shaft 700 between spacing collars and the shaft 1301 is similarly formed for the accommodation of coupler bars at various locations. As in the Gooch construction a bail 1316 is pivotally mounted between the supporting side plates 710 with its outer cross-bar extending above the forward ends of the coupler bars or levers 1315, a spring 1383 tending to lower the bail and thereby depress the forward ends of these coupler bars elevating their rear ends and affecting the splits. The rear portions of the coupler bars are normally held in engagement with the latches by springs 1381 connecting their forward ends with overhanging arms 1317, these springs, however, being inferior in combined strength to the spring 1383. The arms 1317 are formed with open key-hole slots 1317^a so that they may be detachably mounted upon the inner cross-bar of the bail 1316 as shown in Fig. 5, and said arms are held from lateral displacement by engagement between spacing collars of the shaft 1301 next adjacent those between which the coupler bars 1315 engage. These

arms are offset as shown in Fig. 6 to bring their rear ends in vertical alinement with the coupler bars and downward movement of the arms is prevented by their abutment against the shaft 1301 as shown in Fig. 5. It will be seen that with this arrangement the arms can be located wherever required by the presence of coupler bars.

The spring 1383 is normally prevented from depressing the bail by reason of the engagement under a stud 1352 on the bail of a hook 1310^a at the lower end of a vertically sliding bar 1310 upheld by a spring 1388 (Fig. 2) which is superior to said spring 1383. It will be obvious that the lowering of this bar 1310 will bring about the splitting of the machine by permitting the spring 1383 to pull down the bail and lift the rear ends of the coupler bars. Said bar 1310 extends up between cross-rods 200 and 201 just below the key-board plates 212 and 213, said cross-rods supporting a bridge piece 1320 to which the upper end of the spring 1388 is attached. Between the key-board plates 212 and 213 are secured bearings 1321 for a shaft 1300 upon which is secured a cam-piece 1336 (Figs. 2 and 4). The spring 1388 holds the upper end of the bar 1310 against the acting periphery of this cam-piece, which periphery comprises three steps graduated in distance from the shaft 1300 and intervening cam edges. This provides for three positions of said bar 1310 the highest of course being attained when the upper end of said bar is resting against the lower step of the cam-piece 1336 as shown in Figs. 2 and 4. A finger-piece 1335 in the form of a milled disk is secured to the shaft 1300 and protrudes through a slot in the upper key-board plate 213 as well as through a slot in the lower key-board plate 212. A suitable plate 1318 forms a frame-piece surrounding the disk 1335 where the latter protrudes above the upper key-board plate 213, as shown in Fig. 3, and the disk bears three inscriptions corresponding in location with the three seats on the cam-piece 1336. When the lowest one of said seats is engaged with the bar 1310 the inscription "Nor" appears on the finger-piece indicating that the machine is at normal *i. e.* without split. The shaft 1300 can be readily turned by rolling the disk 1335 through finger pressure on its milled periphery. Thus the bar 1310 may be depressed until the intermediate step of the cam-piece 1336 is engaged with its upper end. This has the effect of lowering the bail 1316 in the manner already described and effecting the split or splits. The rolling of the disk 1335 productive of this result brings to view another inscription on its periphery such for example as the abbreviation "Nos." indicating that a column of numbers is to be printed in association with amounts and a

total printed at the foot of each column. The third adjustment of the finger-piece brings to view a different inscription such for example as the word "Dates" indicating that not only is a split effected but the total printing eliminated at the left of the split. This third adjustment of the finger-piece involves a further turning if the shaft 1300 and further depression of the bar 1310 until its upper end engages the highest seat of the cam-piece 1336. Such further depression of said bar 1310 has no effect upon the bail 1316 which has already, under the "Nos." adjustment, been depressed far enough to accomplish its function of elevating the rear ends of the coupler bars 1315. This further lowering of the bar 1310 does, however, release devices now to be described which effect the elimination of total printing to the left of the split.

The bar 1310 is formed with a laterally projecting flange or ledge 1319 which normally forms an abutment or catch for the upper end of the curved arm of a lever 1311 pivoted to one of the side plates 710 as shown in Figs. 2 and 8, said curved arm having at its upper extremity an abbreviated lip or flange 1311^a projecting toward the bar 1310 for contact with the front edge of the flange 1319. The location of the latter and the vertical extent of said lip are such that when the bar 1310 is in its uppermost and its intermediate adjustments the engagement is maintained so that no rearward movement of the curved arm of the lever 1311 can take place. However, when the bar 1310 is moved to its lowermost position as shown in Fig. 7 the ledge or flange 1319 is carried below the lip 1311^a so as to no longer obstruct the lever 1311. The arm of the latter extending in rear of its pivot carries a laterally projecting roller 1332 which overlies the tail of the last latch 717 to the left as shown in Fig. 6, so that when the lever 1311 swings in a direction to lower its rearwardly extending arm this latch will be disengaged from the associated hammer driver and will in turn trip the latch or latches to the right up to the line of split. However, this tripping of latches does not result in an action of the associated hammers capable of making an imprint. This is explained as follows: When a total is to be printed by the operation of a left-hand section or division of the split machine the latches of that section are tripped by the pawls 718 and this does not take place until after the restoring bail 712 has moved to the upper end of its regular excursion. Consequently the springs 780 are free to instantly act upon the tripping of the latches and effect the quick blow of the hammers which is essential to the making of the imprint, it being understood that there is a percussive action of the hammers. Now the tripping of the

left-hand latches by the lever 1311 takes place at an early stage in the operation of the machine when the restoring bail 712 is still in engagement with the hammer drivers. Consequently the springs 780 are not free to effect the quick printing blow but the hammers simply move rearward as permitted by the rise of said restoring bail. This precludes a printing action and hence under the "Dates" adjustment there can be no printing of totals by the left-hand section or division of the split machine.

It will of course be understood that this elimination of printing in a left-hand section of the machine when split is only called into play when the machine is being operated to take a total of amounts listed to the right of the split. Consequently the lever 1311 is under the control of the total key. To this end a link 1313 connects the curved arm of said lever with an arm 1312 secured to the rock-shaft 204 which carries the total key lever 227L. The link is longitudinally slotted at its forward end for engagement with a stud 1357 on said arm 1312 and the usual total key spring 288 normally holds the stud at the forward end of the slot thus preventing rearward movement of the link and holding forward the curved arm of the lever 1311 and its rearwardly extending arm upward. A spring 1311^b connects the curved arm of the lever 1311 with one of the side plates 710 for the purpose of swinging said lever in a direction to operate the latches to the left of the split in the manner already described but this spring is inferior to the spring 288 and thus can only operate when the total key is depressed. The slot in the link 1313 of course provides for depression of the total key without corresponding movement of the link and the lever 1311 when the "Normal" or "Numbers" adjustment obtains.

While the total key spring 288 necessarily has sufficient strength to draw forward the link 1313 and restore the lever 1311 to normal position, means are preferably provided for positively effecting this restoration of parts to normal. To one side piece of the rack-restoring frame 613 is secured an abutment piece 1314 of generally triangular contour, the rear edge of which abuts the shaft 600 and the forward edge of which extends behind a roller 1331 on the link 1313. Of course as the rack-restoring frame 613 lowers the link 1313 is relieved from any restraint imposed by reason of engagement between said abutment piece 1314 and the roller 1331 so that in case the total key has been depressed and the finger-piece 1335 is at the "Dates" adjustment elimination of total printing at the left of the split may be brought about in the manner described. When the rack-restoring frame swings forward and upward according to its regular 130

mode of operation, the abutment piece 1313 will act against the roller 1331 and restore the link and lever to normal in an obvious manner. While this abutment piece may thus perform the function of the total key spring 288 it does not perform all the functions of said spring in connection with the link because when the finger-piece 1335 is at the "Dates" adjustment and listing is in progress said abutment piece moves away from the roller 1331 in each operation of the machine and the total key spring must then be relied upon to prevent rearward movement of the link.

15 It will be seen that the manipulative means for determining the conditions under which the machine shall operate are of such character as to provide for indicating by suitable inscriptions the condition of the 20 machine and also to provide for a location of the finger-piece in such relation to the rows of amount keys as to indicate a line of split. Thus as will be seen by reference to Fig. 3 the finger-piece is located just 25 above the top cross line of amount keys intermediate two rows of keys and such location will indicate that the line of split is between denominations represented by these 30 adjacent rows of keys. Of course under the present illustration of the invention this only applies with reference to a single split and it will furthermore be understood that the elimination of total printing as here shown and described applies only to that 35 section of the machine to the left of the first split to the right where more than one split is effected.

However, it will be obvious that various 40 modifications may be made within the scope of the invention not only as to the number and location of splits but as to elimination of total printing. The construction here shown is also susceptible of modification in other particulars within the scope of the invention and the following claims have been 45 framed accordingly.

What is claimed is:

1. In a machine of the character described, the combination of percussive printing mechanism including interacting detents; means for suspending interaction between neighboring detents; and means for preliminarily displacing the first detent of the series to one side of the point of suspension and thereby eliminating percussive action of a part of the printing mechanism.
2. In a machine of the character described, the combination with the total key and means for percussively printing numbers side by side; of means for effecting at will under control of said total key a gradual movement of a predetermined division of such printing means to eliminate imprints, substantially as described.
3. In a machine of the character described,

the combination of means for effecting a split at will; means for percussively printing numbers side by side; and means for effecting under control of the said splitting means a gradual movement of the printing means at one side of the split to eliminate imprints, substantially as described.

4. In a machine of the character described, the combination of a total key; percussive printing devices equipped for subdivision; manipulative means for determining whether or not the printing devices shall be subdivided; and means under the joint control of said total key and said manipulative means for effecting a gradual movement of a division of the printing devices to eliminate imprints.

5. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches, an accumulator, totaling connections between the latter and the type, and means controlled by said totaling connections for tripping a left-hand division of latches prior to the action thereupon of the means for severally tripping them.

6. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, a vibrating member for moving the link and latch-tripping lever in opposition to the spring, and means for controlling the latch-tripping lever by the latch-uncoupling means.

7. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches, an accumulator, totaling connections between the

latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, a vibrating member for moving the link and latch-tripping lever in opposition to the spring, and a catch for restraining said lever carried by the latch-uncoupling means.

8. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and means for controlling the latch-tripping lever by the latch-uncoupling means.

9. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and a catch for restraining said lever carried by the latch-uncoupling means.

55 10. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing co-operative action in cipher-printing, means for severally tripping the latches, manipulative devices for uncoupling adjacent latches, an

accumulator, totaling connections between the latter and the type, and means controlled by said totaling connections for tripping a left-hand division of latches prior to the action thereupon of the means for severally tripping them.

11. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing co-operative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, a vibrating member for moving the link and latch-tripping lever in opposition to the spring, and means for controlling the latch-tripping lever by the latch-uncoupling means.

12. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing co-operative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, a vibrating member for moving the link and latch-tripping lever in opposition to the spring, and a catch for restraining said lever carried by the latch-uncoupling means.

13. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing co-operative action in cipher-printing, means for sever-

ally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and means for controlling the latch-tripping lever by the latch-uncoupling means.

14. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing cooperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and a catch for restraining said lever carried by the latch-uncoupling means.

15. In a machine of the character described, the combination of sets of type, setting up means therefor, hammers to strike the type, means for retracting the hammers, latches for restraining the hammers, couplings between the latches for securing cooperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and means for controlling the latch-tripping lever by the latch-uncoupling means.

16. In a machine of the character described, the combination of sets of type, setting up means therefor, hammers to strike the type, means for retracting the hammers,

latches for restraining the hammers, couplings between the latches for securing cooperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, a vibrating member for moving the link and latch-tripping lever in opposition to the spring, and a catch for restraining said lever carried by the latch-uncoupling means.

17. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing cooperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, a vibrating member for moving the link and latch-tripping lever in opposition to the spring, and a catch for restraining said lever carried by the latch-uncoupling means.

18. In a machine of the character described, the combination of sets of type, setting up means therefor, hammers to strike the type, spring-actuated hammer drivers, means for retracting the latter and the hammers, latches for restraining the drivers and consequently the hammers, couplings between the latches for securing cooperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, a vibrating member for mov-

ing the link and latch-tripping lever in opposition to the spring, and a catch for restraining said lever carried by the latch-uncoupling means.

19. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, and means controlled by said totaling connections for tripping a left-hand division of latches prior to the action thereupon of the means for severally tripping them.

20. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, a vibrating member for moving the link and latch-tripping lever in opposition to the spring, and means for controlling the latch-tripping lever by the latch-uncoupling means.

21. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and

having a slot-and-pin connection with said total key arm, a vibrating member for moving the link and latch-tripping lever in opposition to the spring, and a catch for restraining said lever carried by the latch-uncoupling means.

22. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, and means for controlling the latch-tripping lever by the latch-uncoupling means.

23. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, a lever equipped for engagement with the latch farthest to the left, a spring drawing said lever in a direction to trip said latch, a total key controlling said totaling connections, a swinging arm operated by said key, a link connected with the latch-tripping lever and having a slot-and-pin connection with said total key arm, and a catch for restraining said lever carried by the latch-uncoupling means.

24. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between the latter and the type, a lever equipped for

engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, a vibrating member for moving the link and latch-tripping lever in opposition to the spring, and means for controlling the latch-tripping lever by the latch-uncoupling means.

25. In a machine of the character described, the combination of sets of type, setting up means therefor, hammers to strike the type, spring-actuated hammer drivers, a vibrating bail for retracting the latter and the hammers, latches for restraining the drivers and consequently the hammers, couplings between the latches for securing coöperative action in cipher-printing, means for severally tripping the latches, manipulative devices for uncoupling adjacent latches, an accumulator, totaling connections between 20 the latter and the type, a lever equipped for engagement with the latch farthest to the left, a spring drawing said lever in a direction to trip said latch, a spring-drawn total key controlling said totaling connections, a swinging arm operated by said key, a link connected with the latch-tripping lever and having a slot-and-pin connection with said total key arm, a vibrating member for moving the link and latch-tripping lever in opposition to the spring, and a catch for restraining said lever carried by the latch-uncoupling means.

26. In a machine of the character described, the combination of a key-board having rows of amount keys, printing devices comprising a set for each row of keys, means for producing coöperative action between the sets of printing devices, and means for interrupting at will such coöperative action 45 including a manipulative device on the key-board between rows of amount keys pertaining to the sets of printing devices whose co-action is interrupted.

27. In a machine of the character described, the combination of a key-board having rows of amount keys, printing devices comprising a set for each row of keys, means for producing coöperative action between the sets of printing devices, and means for interrupting at will such coöperative action 55 including a rotatable disk protruding on the key-board between rows of amount keys pertaining to the sets of printing devices whose co-action is interrupted.

60 28. In a machine of the character described, the combination of a key-board having rows of amount keys, printing devices comprising a set for each row of keys, means for producing coöperative action between the sets of printing devices, and

means for interrupting at will such coöperative action, including a rotatable disk protruding on the key-board between rows of amount keys pertaining to the sets of printing devices whose co-action is interrupted, said disk bearing inscriptions to denote the condition of the machine as to co-action between the printing devices.

29. In a machine of the character described, the combination of a keyboard having rows of amount keys, printing devices comprising a set for each row of keys, means for producing coöperative action between the sets of printing devices, and means for interrupting at will such coöperative action including a manipulative device on the keyboard and a stepped cam operated thereby.

30. In a machine of the character described, the combination of a keyboard having rows of amount keys, printing devices comprising a set for each row of keys, means for producing coöperative action between the sets of printing devices, and means for interrupting at will such coöperative action including a rotatable disk protruding on the keyboard and a stepped cam compounded therewith.

31. In a machine of the character described, the combination of a keyboard having rows of amount keys, printing devices comprising a set for each row of keys, means for producing coöperative action between the sets of printing devices, and means for interrupting at will such coöperative action including a rotatable disk protruding on the keyboard and a stepped cam compounded therewith, said disk bearing inscriptions to denote the condition of the machine as to co-action between the printing devices.

32. In a machine of the character described, the combination of impression hammers, latches normally restraining the same and coöperatively related for cipher-printing purposes with one or more movable couplers to provide for splits, a bail for displacing the coupler, a vertically extending slide bar engaging under a portion of said bail, and a stepped cam engaging said bar and suitably equipped for manipulation.

33. In a machine of the character described, the combination of impression hammers, latches normally restraining the same and coöperatively related for cipher-printing purposes with one or more movable couplers to provide for splits, a bail for displacing the coupler, a vertically extending slide bar engaging under a portion of said bail, and a horizontally arranged shaft carrying a finger-piece by which to turn it and a stepped cam engaged with said bar, substantially as and for the purpose described.

34. In a machine of the character de-

scribed, the combination of a series of independently pivoted and spring-actuated impression hammers; a series of independently pivoted latches normally restraining said hammers; means for individually displacing said latches; connections between the latches for causing the displacement of one latch to displace others, said connections including one or more pivotally mounted 5 spring-held coupler bars; a spring-drawn bail extending over said coupler bar and adapted through operation thereon to disconnect adjacent latches; a spring-drawn bar constructed to engage under a portion 10 of the bail and retract the same; and a shaft carrying a manipulating member and a stepped cam engaged with said spring-drawn bar.

35. In a machine of the character described, the combination of a series of independently pivoted and spring-actuated impression hammers; a series of independently pivoted latches normally restraining said hammers; means for individually displacing 20 said latches; connections between the latches for causing the displacement of one latch to displace others, said connections including one or more pivotally mounted spring-held coupler bars; a spring-drawn bail extending over said coupler bar and adapted through operation thereon to disconnect adjacent latches, a vertically extending spring-drawn bar constructed to engage 25 under a portion of the bail and retract the same; and a horizontally extending shaft carrying a manipulating disk and a stepped cam engaged with said spring-drawn bar.

36. In a machine of the character described, the combination of sets of type, setting up means therefor, hammers to strike 40 the type, means for retracting the hammers, latches for restraining the hammers, couplings between the latches for securing co-operative action in cipher-printing, means for severally tripping the latches, manipulative devices for uncoupling adjacent latches including a longitudinally movable bar, an accumulator, totaling connections 45 between the latter and the type, a lever equipped for engagement with the latch farthest to the left but restrained through engagement with said bar under certain adjustment thereof, a spring drawing said lever in a direction to trip said latch when 50 the adjustment of the bar is changed, a total key controlling said totaling connections, a swinging arm operated by said key, a link connected with the latch-tripping lever and having a slot-and-pin connection with said total key arm, and means for moving the link and latch-tripping lever in opposition to the 55 spring.

37. In a machine of the character described, the combination of sets of type, setting up means therefor, hammers to strike 60

the type, means for retracting the hammers, latches for restraining the hammers, couplings between the latches for securing co-operative action in cipher-printing, means for severally tripping the latches, manipulative devices for uncoupling adjacent latches 70 including a longitudinally movable bar, an accumulator, totaling connections between the latter and the type, a lever equipped for engagement with the latch farthest to the left but restrained through engagement with said bar under certain adjustment thereof, a spring drawing said lever in a direction to trip said latch when the adjustment of the bar is changed, a spring-drawn 75 total key controlling said totaling connections, a swinging arm operated by said key, and a link connected with the latch-tripping lever and having a slot-and-pin connection with said total key arm.

38. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent latches including a longitudinally movable bar, an accumulator, totaling connections 90 between the latter and the type, a lever equipped for engagement with the latch farthest to the left but restrained through engagement with said bar under certain adjustment thereof, a spring drawing said lever in a direction to trip said latch when the adjustment of the bar is changed, a spring-drawn total key controlling said totaling connections, a swinging arm operated by said key, and a link connected with the latch-tripping lever and having a slot-and-pin connection with said total key arm, and a vibrating member for moving the link and latch-tripping lever in opposition to the 95 spring.

39. In a machine of the character described, the combination of sets of type, setting up means therefor, hammers to strike the type, means for retracting the hammers, latches for restraining the hammers, couplings between the latches for securing co-operative action in cipher-printing, means for severally tripping the latches, manipulative devices for uncoupling adjacent 105 latches including a longitudinally movable bar spring-drawn in a direction to enable the coupling and a stepped cam for moving the bar in the opposite direction, an accumulator, totaling connections between the latter and the type, a lever equipped for engagement with the latch farthest to the left but restrained through engagement with said bar under certain adjustment thereof, a spring drawing said lever in a direction 110

120

125

130

- to trip said latch when the adjustment of the bar is changed, a total key controlling said totaling connections, a swinging arm operated by said key, a link connected with the latch-tripping lever and having a slot-and-pin connection with said total key arm, and means for moving the link and latch-tripping lever in opposition to the spring.
40. In a machine of the character described, the combination of sets of type, setting up means therefor, hammers to strike the type, means for retracting the hammers, latches for restraining the hammers, couplings between the latches for securing coöperative action in cipher-printing, means for severally tripping the latches, manipulative devices for uncoupling adjacent latches including a longitudinally movable bar spring-drawn in a direction to enable the coupling and a stepped cam for moving the bar in the opposite direction, an accumulator, totaling connections between the latter and the type, a lever equipped for engagement with the latch farthest to the left but restrained through engagement with said bar, under certain adjustment thereof, a spring drawing said lever in a direction to trip said latch when the adjustment of the bar is changed, a spring-drawn total key controlling said totaling connections, a swinging arm operated by said key, and a link connected with the latch-tripping lever and having a slot-and-pin connection with said total key arm.
41. In a machine of the character described, the combination of sets of type, setting up means therefor, hammers to strike the type, means for retracting the hammers, latches for restraining the hammers, couplings between the latches for securing coöperative action in cipher-printing, means for severally tripping the latches, manipulative devices for uncoupling adjacent latches including a longitudinally movable bar spring-drawn in a direction to enable the coupling and a stepped cam for moving the bar in the opposite direction, an accumulator, totaling connections between the latter and the type, a lever equipped for engagement with the latch farthest to the left but restrained through engagement with said bar under certain adjustment thereof, a spring drawing said lever in a direction to trip said latch when the adjustment of the bar is changed, a spring-drawn total key controlling said totaling connections, a swinging arm operated by said key, and a link connected with the latch-tripping lever and having a slot-and-pin connection with said total key arm.
42. In a machine of the character described, the combination of impression hammers, latches normally restraining the same and coöperatively related for cipher-printing purposes with one or more movable couplers to provide for splits, a bail for displacing the coupler, a vertically extending slide bar engaging under a portion of said bail, a stepped cam engaging said bar and suitably equipped for manipulation, means for retracting the hammers, sets of type, setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a total key controlling said totaling connections, a swinging arm operated by said key, a link connected with the latch-tripping lever and having a slot-and-pin connection with said total key arm.
43. In a machine of the character described, the combination of impression hammers, latches normally restraining the same and coöperatively related for cipher-printing purposes with one or more movable couplers to provide for splits, a bail for displacing the coupler, a vertically extending slide bar engaging under a portion of said bail, a stepped cam engaging said bar and suitably equipped for manipulation, means for retracting the hammers, sets of type, setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a spring-drawn total key controlling said totaling connections, a swinging arm operated by said key, and a link connected with the latch-tripping lever and having a slot-and-pin connection with said total key arm.
44. In a machine of the character described, the combination of impression hammers, latches normally restraining the same and coöperatively related for cipher-printing purposes with one or more movable couplers to provide for splits, a bail for displacing the coupler, a vertically extending slide bar engaging under a portion of said bail, a stepped cam engaging said bar and suitably equipped for manipulation, means for retracting the hammers, sets of type, setting up means therefor, an accumulator, totaling connections between the latter and the type, a lever equipped for en-

gagement with the latch farthest to the left but restrained by abutment against the aforesaid slide bar under certain adjustment thereof, a spring drawing said lever 5 in a direction to trip the latch when said bar is differently adjusted, a total key controlling said totaling connections, a swinging arm operated by said key, a link connected with the latch-tripping lever and 70 having a slot-and-pin connection with said total key arm, and a vibrating member for moving the link and latch-tripping arm in opposition to the spring.

45. In a machine of the character described, the combination of impression hammers, latches normally restraining the same and co-operatively related for cipher-printing purposes with one or more movable couplers to provide for splits, a bail for 15 placing the coupler, a vertically extending slide bar engaging under a portion of said bail, a stepped cam engaging said bar and suitably equipped for manipulation, means for retracting the hammers, sets of type, 20 setting up means therefor, an accumulator, totaling connections between the latter and the type, a lever equipped for engagement with the latch farthest to the left but restrained by abutment against the aforesaid 25 slide bar under certain adjustment thereof, a spring drawing said lever in a direction to trip the latch when said bar is differently adjusted, a spring-drawn total key controlling said totaling connections, a swinging 30 arm operated by said key, a link connected with the latch-tripping lever and having a slot-and-pin connection with said total key arm, and a vibrating member for moving the link and latch-tripping arm in opposition to the spring.

46. In a machine of the character described, the combination of a series of independently pivoted and spring-actuated impression hammers; a series of independently 45 pivoted latches normally restraining said hammers; means for individually displacing said latches; connections between the latches for causing the displacement of one latch to displace others, said connections including one or more pivotally mounted spring-held coupler bars; a spring-drawn bail extending over said coupler bar and adapted through operation thereon to disconnect adjacent latches; a spring-drawn 50 bar constructed to engage under a portion of the bail and retract the same; a shaft carrying a manipulating member and a stepped cam engaged with said spring-drawn bar, means for retracting the hammers, sets of type, 55 setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a spring-drawn total key controlling said totaling connections, a swinging arm operated by said key, and a link connected with the latch-tripping lever and having slot-and-pin connection with said total key arm.

47. In a machine of the character described, 75 the combination of a series of independently pivoted and spring-actuated impression hammers; a series of independently pivoted latches normally restraining said hammers; means for individually displacing said latches; connections between the latches for causing the displacement of one latch to displace others, said connections including one or more pivotally mounted spring-held coupler bars; a spring-drawn bail extending over said coupler bar and adapted through operation thereon to disconnect adjacent latches; a spring-drawn bar constructed to engage under a portion of the bail and retract the same; a shaft carrying a manipulating member and a stepped cam engaged with said spring-drawn bar, means for retracting the hammers, sets of type, 80 setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a spring-drawn total key controlling said totaling connections, a swinging arm operated by said key, and a link connected with the latch-tripping lever and having slot-and-pin connection with said total key arm.

48. In a machine of the character described, the combination of a series of independently pivoted and spring-actuated impression hammers; a series of independently pivoted latches normally restraining said hammers; means for individually displacing said latches; connections between the latches for causing the displacement of one latch to displace others, said connections including one or more pivotally mounted spring-held coupler bars; a spring-drawn bail extending over said coupler bar and adapted through operation thereon to disconnect adjacent latches; a spring-drawn bar constructed to engage under a portion of the bail and retract the same; a shaft carrying a manipulating member and a stepped cam engaged with said spring-drawn bar, means for retracting the hammers, sets of type, 90 setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a spring-drawn total key controlling said totaling connections, a swinging arm operated by said key, and a link connected with the latch-tripping lever and having slot-and-pin connection with said total key arm.

49. In a machine of the character described, the combination of a series of independently pivoted and spring-actuated impression hammers; a series of independently pivoted latches normally restraining said hammers; means for individually displacing said latches; connections between the latches for causing the displacement of one latch to displace others, said connections including one or more pivotally mounted spring-held coupler bars; a spring-drawn bail extending over said coupler bar and adapted through operation thereon to disconnect adjacent latches; a spring-drawn bar constructed to engage under a portion of the bail and retract the same; a shaft carrying a manipulating member and a stepped cam engaged with said spring-drawn bar, means for retracting the hammers, sets of type, 100 setting up means therefor, an accumulator, totaling connections between the latter and the type, a lever equipped for engagement with the latch farthest to the left but restrained by abutment against the aforesaid slide bar under certain adjustment thereof, a spring drawing said lever in a direction to trip the latch when said bar is differently adjusted, a spring-drawn total key controlling said totaling connections, a swinging arm operated by said key, and a link connected with the latch-tripping lever and having slot-and-pin connection with said total key arm.

- thest to the left but restrained by abutment against the aforesaid slide bar under certain adjustment thereof, a spring drawing said lever in a direction to trip the latch 5 when said bar is differently adjusted, a total key controlling said totaling connections, a swinging arm operated by said key, a link connected with the latch-tripping lever and having slot-and-pin connection with said 10 total key arm; and a vibrating member for moving the link and latch-tripping arm in opposition to the spring.
49. In a machine of the character described, the combination of a series of independently pivoted and spring-actuated impression hammers; a series of independently pivoted latches normally restraining said hammers; means for individually displacing said latches; connections between the 15 latches for causing the displacement of one latch to displace others, said connections including one or more pivotally mounted spring-held coupler bars; a spring-drawn bail extending over said coupler bar and 20 adapted through operation thereon to disconnect adjacent latches; a spring-drawn bar constructed to engage under a portion of the bail and retract the same; a shaft carrying a manipulating member and a stepped 25 cam engaged with said spring-drawn bar, means for retracting the hammers, sets of type, setting up means therefor, an accumulator, totaling connections, between the lat-
- ter and the type, a lever equipped for engagement with the latch farthest to the left 35 but restrained by abutment against the aforesaid slide bar under certain adjustment thereof, a spring drawing said lever in a direction to trip the latch when said bar is differently adjusted, a spring-drawn total 40 key controlling said totaling connections, a swinging arm operated by said key, a link connected with the latch-tripping lever and having slot-and-pin connection with said total key arm, and a vibrating member for 45 moving the link and latch-tripping arm in opposition to the spring.
50. In a machine of the character described, the combination of percussive printing mechanism having impression devices 50 coöperating to print ciphers; means for interrupting and restoring such coöperation at will at one or more points; accumulating mechanism; means for returning the accumulator to zero and thereby setting up totals 55 or subtotals; and means for eliminating percussive action in the printing mechanism to one side of the point of interruption of co-operation between impression devices, when a total is set up, as controlled by the means 60 for effecting such interruption.
